UNITED STATES PATENT OFFICE.

FIDELIS M. MECHLING, OF WICHITA, KANSAS.

SAFETY CAP FOR OIL WELLS.

Application filed December 1, 1924. Serial No. 753,232.

This invention pertains to safety caps for oil wells and the like.

In certain oil well operations such, for instance, as drilling in a well when the gas or oil is flowing, it is customary to provide a cap or seal for the upper end of the well casing and through which the cable works so as to reduce or cut off the flow of gas or oil from the well. Such devices are of various types of which the ordinary sand cap and the oil saver are well known in the art. During such operations it frequently becomes necessary to lift the tools or other implements suspended from the cable out of the well. It is customary in such cases to place a suitable mark on the cable some distance above the implements so that when this mark emerges from the well the operator will be warned that the end of the cable is near. It frequently happens, however, through accident or carelessness, that this mark is disregarded and the end of the cable arrives at the top of the well without warning, bringing the tools forcibly against the sealing cap, so as usually to destroy the cap and tear it from the casing. Occasionally the cable may be broken by the impact and the implements dropped to the bottom of the well.

One of the objects of this invention, therefore, is to provide a safety cap for the well casing which may be operated by the cable to release the same from the casing when engaged by a suitably arranged part on the cable.

Another object is to provide a cap which may be assembled on the cable while in the well.

Another object is to provide such a device which may be set in locking position and engaged with the casing head in that position.

Further objects will appear from the following description taken in connection with the accompanying drawing, in which:

Figure 1 is a view partly in elevation and partly in section showing a safety cap embodying this invention as mounted on the well casing. This section is taken on line 1-1 of Figure 2, except that the ring 5 and the head 1 are shown in diametrical section.

Figure 2 is a section on line 2-2 of Figure 1; and

Figure 3 is a detail of the retaining ring. Referring to the accompanying drawing 1 designates a casing head which may be provided with a packing ring 2 and an upstanding flange 3 in which are mounted locking screws 4, for retaining the retaining ring 5. The retaining ring 5 is adapted to rest on the packing ring 2 and may be provided with a tapered flange 6 adapted for engagement by the screws 4 to lock the retaining ring in place on the casing head and to force the same into firm engagement with the ring 2. The retaining ring 5 may also be provided with a packing ring 7 and an upstanding flange 8. The bore of the ring 5 is provided with one or more inwardly extending lugs 9 extending circumferentially around the inner bore of the ring and provided with a sloping lower face 10 for a purpose which will be hereinafter more fully described.

Mounted in the retaining ring and so as to rest upon the packing ring 7 and within the flange 8 is a box 11 having a split body constructed in two half parts and provided with lugs 12 adapted to receive bolts 13 for clamping the half parts together. The box 11 may also be provided with a packing ring 14 and a flange 15 carrying locking screws 16 adapted for engagement with the lower flange 17 of an oil saver or other similar casing cap 18. It will be seen that by virtue of the various packing rings 2, 7 and 14 and the cap 18 the casing is completely sealed against the escape of gas or oil.

The box 11 is provided with a series of radial channels 19, formed by downwardly extending flanges 190 on the lower end of the box 11, and adapted to receive a series of dogs 20 for sliding movement therealong. The dogs 20 are thus arranged to slide outwardly to the positions shown in dotted lines in Figure 2 or to be retracted to a position shown in solid lines in Figure 2. Each dog is provided with an opening 21 having beveled faces adapted for engagement by the similarly beveled faces of the prongs 22 of a fork or spider 23 mounted on the end of a vertical sleeve 24 which is mounted for sliding movement as will presently be described.

The sleeve 24 has a split body so that it may be assembled around the cable and bolted together by bolts 25 engaging lugs 26. This sleeve is provided with a central cable channel 27 in alinement with the cable channel 28 in the box 11. The sleeve 24 has a smooth cylindrical outer surface 29 having a sliding bearing in a collar 30 forming part of an extension 40 of the box 11. The extension 40 is also made in two half parts provided with lugs 41 for holding the parts together and with bolt holes adapted to receive bolts 42 for bolting the extension 40 on to the main body of the box 11. Thus bolting the extension 40 on to the main body of the box 11 completes the channels 19 in which the dogs 20 move.

The sleeve 24 is further provided with a pair of lugs 43 in which are mounted a pair of guide studs 44 each adapted to move in a guiding channel 45 formed in the extension 40. Each stud 44 is surrounded by a coil spring 46 bearing against the lug 43 and the end of the extension 40 so as to force the sleeve 24 downwardly in Figure 1. It will be seen that as the sleeve 24 is moved downwardly in Figure 1 the prongs 22, cooperating with the beveled faces of the openings 21, will move the dogs 20 outwardly to locking position as shown in dotted lines in Figure 2. These dogs are shown in retracted or unlocking position in Figure 1.

In mounting this device on the casing head, the retaining ring 5 being in position on said head, the box 11 with its assembled parts is set into the retaining ring 5. In this operation the dogs 20, which are maintained in locking position by reason of the fact that the springs 46 maintain the sleeve 24 in its downward position Figure 1, are passed through the openings 47 between the lugs 9 of the retaining ring. When the box has come to a seat on the packing ring 7 the ends of the dogs will be in a position to take under the ends of the lugs 9, and rotation of the box in a clockwise direction will force the dogs against the wedging underfaces 10 of the lugs 9 so as to draw the box firmly down upon the packing ring 7 and secure the same firmly on the casing head. The normal operation of the well such as drilling or the like is carried on with the device in this position, the cable passing through the cable channel 27 and 28.

When it becomes necessary to raise the tools from the well the cable is simply hauled up until the tools reach the top of the well. In many cases a dog or stop is fixed on the cable a short distance above the tools. This stop, or in its absence the tools themselves, will then come into engagement with the lower end of the sleeve 24. This will raise the sleeve against the tension of the springs 46. Raising of the sleeve will

force the prongs 22 to retract the dogs 20 so that the latter will move out of engagement with the lugs 9 of the retaining ring thereby releasing the box 11 and the cap 18 from connection with the casing head. Upon such release, of course, the box will be carried upwardly with the tools as they emerge from the well.

It will be seen, therefore, that this invention provides a simple and effective device for protecting the casing cap against accidental damage by being struck by implements rising from the well. The device may be assembled on the cable after the same is in the well so that it is not necessary to remove the well tools and thread the cable through the device. After assembly it is conveniently and quickly set in place and locked to the casing head. While in place it serves as an effective seal against the escape of gas or oil and when the tools are lifted from the well it is quickly released from connection with the casing head upon engagement by the tools or other part on the cable.

While the drawing shows the device in use with an oil saver as a casing cap, it will be understood that any type of casing cap such as an oil saver, the ordinary sand cap, or any other type of casing cap may be used.

It is obvious that various changes may be made in the details of construction without departing from the spirit of this invention; it is to be understood, therefore, that this invention is not to be limited to the specific details shown and described.

Having thus described the invention what is claimed is:

1. A device of the character described, comprising, a split box having a cable channel and adapted for assembly around the cable and for mounting on the casing head, a seat on said box, a casing cap seated thereon, and means for securing said box on the casing head adapted for automatic release by a part on the cable.

2. A device of the character described, comprising, a retainer on the casing head, a split box adapted for mounting on the casing head and for assembly around the cable, a seat on said box and a cap seated thereon, a dog on said box adapted to engage said retainer, and means adapted for automatic actuation by a part on the cable to release said dog.

3. A device of the character described, comprising, a retainer on the casing head, a box adapted for mounting on said retainer and having a cable channel, packing between said box and said retainer, wedging means for locking said box on said retainer and against said packing, and means adapted for operation by a part on the cable for releasing said locking means.

4. A device of the character described, comprising, a retainer on the casing head, a split box having a cable channel adapted for mounting on said retainer and provided with a seat for receiving a casing cap, packing between said box and said retainer, wedging means for locking said box on said retainer and against said packing, and means adapted for operation by a part on the cable for releasing said locking means. 10
- 5

In testimony whereof I affix my signature this 17th day of November, 1924.

FIDELIS M. MECHLING.
